United States Patent Office.

JOEL D. WEAVER, OF TROY, NEW YORK, ASSIGNOR TO HIMSELF, C. A. SHERWOOD, AND L. S. BUNNELL, OF SAME PLACE.

Letters Patent No. 80,888, dated August 11, 1868.

IMPROVEMENT IN SPIRIT-METERS.

The Schedule referred to in these Letters Patent and making part of the same.

TO ALL WHOM IT MAY CONCERN:

Be it known that I, JOEL D. WEAVER, of Troy, in the county of Rensselaer, and State of New York, have invented a new and useful Improvement in Spirit-Meters; and I do hereby declare that the following is a full, clear, and exact description thereof, which will enable others skilled in the art to make and use the same, reference being had to the accompanying drawings, forming part of this specification, in which—

Figure 1 represents a plan view of my improved machine.

Figure 2 represents a longitudinal elevation, and

Figure 3 represents a plan of the valve-seat, showing the ports and the valve.

Similar letters of reference indicate corresponding parts.

The nature of this invention relates to improvements in that class of meters for measuring fluids which consist of a piston working within a cylinder.

It consists of an improved arrangement of mechanism for operating the valve; also in an improved valve.

Hitherto this class of meters have been found to some extent objectionable, in consequence of the imperfect operation of the valves, which it is the object of my invention to overcome.

On reference to the drawings, A represents a cylinder, provided with a piston, B, the rod C of which projects through stuffing-boxes at both ends, and which carries at each end a curved arm, D, securely connected thereto.

E represents a slide-rod supported by the said arms in a vertical plane above the said piston-rod.

F represents guides rising upward from the top of the cylinder, and provided with grooves, wherein the said slide E is reciprocated by the piston-rod.

G represents a tube which is supported by brackets, H, projecting from the arm E, one at each end; a reciprocating movement is therefore communicated to the said tube by the slide E.

I represents the valve-chest, which is of cylindrical form, and having a vertical axis. In the bottom of the said valve-chest are the ports. a is the port communicating with the receiving-tube b, a¹ and a² the ports leading to the cylinder, and a³ the exhaust-port.

K represents a circular valve, which is fitted to work steam-tight in the cylindrical valve-chest I, and arranged to oscillate in a horizontal plane. It is provided with a curved opening, c, through it, in a vertical direction, and a recess, d, in its lower face, of the same size and form of the opening, and on the opposite side to the same. The said valve is also provided with a vertical stem, e, which is seated in a step at its lower end in the bottom of the valve-chest. The upper end, projecting through a stuffing-box in the cap of the chest, is connected to an arm, f, the outer end of which projects through a central opening in the tube G. The hub of the said arm is provided with a vertical segmental spur or flange, g, having two radial grooves, g¹ and g², through it. The portion h of the flange, which separates the grooves, is not as high as the outer portions thereof, h¹ and h².

The slide-rod E is provided with two notches, d and d', in its lower edge, and the tube G is provided with spiral springs K and K', one in each end, arranged to bear upon each side of the arm f of the valve K.

When the valve is set in position, care is taken to arrange it so that when the slide-bar rests in the groove g² of the flange g, the passage C will be coincident with the receiving-port a, and the port a², leading into the cylinder. The fluid to be measured being now admitted through the pipe b, will flow through the ports a and a² into the cylinder, whereby the piston will be driven to the left, thereby pressing the spring K' against the right side of the arm f. As the piston arrives near the end of its stroke in that direction, the notch d' in the slide E will be brought to a position coincident with the spur h of the flange g, thereby relieving the resistance it has maintained against the action of the spring K', which will instantly throw the said arm around, bringing the groove g¹ coincident with the slide-rod, and changing the position of the valve, so as to change the passage of the fluid from port a to the port a¹, and opening the port a² to the exhaust a³. The piston will now move to

the right, and the spring K will be compressed against the arm f, ready to change the valve back again to the first-named position as soon as the notch d arrives at a point coincident with the stud h. This operation will continue as long as the fluid is fed to the machine.

A registering-apparatus may be actuated from the reciprocating parts of the machine, in any suitable manner.

As the action of the valve is sudden and positive, the utmost accuracy of measurement may be attained without regard to the amount of pressure.

In practice, a metal packing may be provided at the upper end of the valve, that will, when laid upon the valve, be slightly higher than the wall of the valve-chest I, upon which the cap of the chest may be accurately adjusted, the joint between the cap and the top of the chest being packed with a yielding packing.

In consequence of the passage C being made entirely through the valve, the upward pressure which would be due to the area of the same, were it a recess, as is provided for the exhaust, is entirely removed from the valve and expended upon the packing above, and the downward pressure is expended against the valve-seat and the ports, whereby the valve is always balanced, irrespective of the amount of pressure of the propelling medium.

My improved apparatus may also be used with great facility as a motor, and may be operated either by water or steam, and will be found especially useful for propelling pumps for raising water, or as a ram.

A pump-cylinder may be attached to one of the piston-heads, or may be cast with it, or, if a double-acting pump is desired, such cylinders may be attached to each piston-head, and the piston-rod be provided near each end with plungers for the pumps, and with reduced prolongations projecting through stuffing-boxes at the outer ends of the pumps, for communicating motion to the rod E, and a portion of the water for operating it may be raised thereby in a very simple manner.

Having thus described my invention, I claim as new, and desire to secure by Letters Patent—

1. The improved valve-actuating mechanism, substantially such as herein shown and described for the purpose set forth.
2. The improved valve K, in combination with the valve-chest I, provided with ports, arranged substantially as and for the purpose described.
3. The combination of the sliding rod E, valve-stem e, and spring-actuated arm f, substantially as and for the purpose described.
4. The combination, with the arm f, of the tube G, provided with the springs K and K', and actuated by the slide E, substantially as and for the purpose described.

The above specification of my invention signed by me, this 23d day of April, 1868.

JOEL D. WEAVER.
